UNITED STATES PATENT OFFICE

WILLARD H. RUSSELL, OF LOS ANGELES, CALIFORNIA

CAPO TASTO

Application filed October 29, 1927. Serial No. 229,652.

This invention relates to a device which is removably mounted on the neck of a stringed instrument for the purpose of changing the key to enable the player to 5 play in different keys without changing the fingering.

An object of my invention is to provide a capo tasto of the character stated which firmly clamps the strings and which can be 10 adjusted to suit the size of the instrument neck.

Another object is to provide a capo tasto which will not mar the instrument and which can be moved along the finger board 15 without removal from the instrument.

Other objects, advantages, and features of invention may appear from the accompanying drawing, the subjoined detailed description, and the appended claims.

20 In the drawing:

Fig. 1 is a fragmentary, perspective view of a stringed instrument with my capo tasto in position thereon.

Fig. 2 is a plan view of the capo tasto.

25 Fig. 3 is a longitudinal sectional view of a modified form of my capo tasto taken on a line substantially as 3—3, Figure 2.

Fig. 4 is a side view of a slightly modified form of capo tasto.

30 Referring more particularly to the drawing:

My capo tasto 1 comprises a soft rubber block 2 which presses against the strings of the instrument. A rigid reinforcing plate 3 is positioned inside of or on top of the block 2 and the block is secured to or molded around the plate. Lugs 4, 4 extend outwardly from either end of the plate 3 and project beyond the block 2, the purpose of 40 which will be further described.

An elastic strip 5 is secured at one end of one lug, extends over the top of the block 2, and thence over the other lug 4, and is then wrapped around the neck 6 of the instrument, the required tension being provided by a plurality of eyelets 7 positioned in the strip 5. The lugs 4 are adapted to extend into the eyelets 7 to hold the capo tasto securely in position.

50 It will be seen that the spaced eyelets 7

will permit of various tensions on the block 2 and, also, these eyelets will permit my capo tasto to be positioned on instruments having different necks.

In Figure 4 I have shown a form of capo 55 tasto in which a metal reinforcing cup 8 is provided, into which the block 2 fits and pins 9, 9 extend into either end of the block upon which the eyelets 7 are hooked to hold the capo tasto in position. 60

Having described my invention, I claim.

1. A capo tasto comprising a rubber block, an elastic strip secured to the block at one end thereof, and means adjustable securing the free end of the strip to the capo tasto 65 whereby the capo tasto is held on the instrument.

2. A capo tasto comprising a rubber block, reinforcing means in said block, an elastic strip secured at one end to the block, eyelets in the strip, and means on the block upon which the eyelets are hooked to secure the strip around the neck of the instrument to hold the capo tasto in position. 70

3. A capo tasto comprising a rubber block, reinforcing means in which said block is mounted, an elastic strip secured at one end to the block, eyelets in the strip, and pins extending from the ends of said block upon which the eyelets are hooked to secure the strip around the neck of the instrument to hold the capo tasto in position. 75

In testimony whereof, I affix my signature.

WILLARD H. RUSSELL. 85
